UNITED STATES PATENT OFFICE.

FREDERICK C. FISK, OF WILLIAMSVILLE, NEW YORK

METHOD OF MANUFACTURING SPARK-PLUGS.

333,400.

Specification of Letters Patent. Patented Mar. 9, 1920.

Application filed June 20, 1919. Serial No. 305,681.

To all whom it may concern:

Be it known that I, FREDERICK C. FISK, a citizen of the United States of America, residing in the town of Williamsville, county 5 of Erie, and State of New York, have invented certain new and useful Improvements in Methods of Manufacturing Spark-Plugs, of which the following is a full, clear, and exact description.

10 My invention relates generally to a method of manufacturing spark plugs, and more particularly to that type of spark plug in which an auxiliary spark gap is provided.

In making spark plugs of this type, glass 15 is usually used as the insulating material because of its transparency and fluidity when in the molten state. The auxiliary spark gap is usually formed at some distance from the exposed ends of the electrodes of the spark plug and difficulty is experienced in properly supporting the electrodes, so that they will remain in the proper alinement when the glass is poured within the matrix and around them. It is also difficult 20 to prevent the molten glass from flowing in between the auxiliary spark gap in the ordinary method of manufacturing such plugs.

The general object of my invention has been to provide a method in which the insulators for such plugs may be easily and 30 quickly made, and in which the inner ends of the electrodes, in the auxiliary spark gap, shall be positively held in alinement and in predetermined relation with each other.

35 In the accompanying drawings, forming part of this application, I have shown one part of an apparatus for carrying out my method; and, it is clear, that any other suitable molding apparatus may be used.

40 In the drawings:

Figure 1 represents the face view of one part of the molding flask showing the electrodes in position.

Fig. 2 shown a fragmentary portion of the 45 same part, with the insulator molded and in section.

In the drawings 5 represents one portion of the customary two-part molding flask, which is, of course, provided with the pouring opening, not shown. 6 is the matrix of the flask which is of a shape to provide any desired form of insulator, the form shown being one in which a taper is provided at

each end of the insulator with an annular flange near the middle portion thereof. 55

7 and 8 are annular supporting disks which are centrally arranged within recesses 9 and 10, respectively. These recesses are formed within the parts of the flask, and preferably a slight distance from the ends 60 of the matrix 6, with walls 11 therebetween. Each of the disks is provided with a central aperture 12 and a set screw 13, whereby the exposed ends of the electrodes 14 and 15 may be suitably clasped and held. The inner 65 ends of each of the electrodes is preferably provided with a peripherally reduced portion 16, whereby a shoulder 17 is formed on each. 18 is a perforated, hollow, glass sphere or a perforated bead, in the oppositely arranged openings of which are disposed the portions 16 of the electrodes. The shoulders 17 are so positioned as to provide a predetermined spark gap between the ends 70 of the electrodes when the shoulders are 75 pressed in contact with the outer surface of the bead. The electrodes are, of course, held in this predetermined position by the disks 7 and 8.

When my process is carried out by the apparatus herein shown and described, the parts of the flask and the electrodes are, of course, first heated. The portion 16 of the electrodes are placed in position within the bead 18 and the outer ends of the electrodes 85 are then placed in position and firmly secured within the disks 7 and 8. The disks are then placed within the recesses 9 and 10 and the flask closed. The molten glass is now poured within the matrix and surrounds the electrodes and glass sphere 18. The temperature of the molten glass will be sufficient to fuse with the glass bead 18 and 90 make the same an integral part of the insulator. After the flask has become sufficiently cooled it may be opened and the insulator easily and quickly removed therefrom. 95

Having thus described my invention what I claim is:

1. A method of manufacturing spark plugs which consists in placing the inner ends of the electrodes in the perforations of a transparent sphere and leaving between the ends a space for the spark gap, then 105 placing the electrodes and the sphere within

the matrix of the flask, and then pouring molten insulating material within the matrix and around the electrodes and sphere.

2. A method of manufacturing spark plugs which consists in placing the inner ends of the electrodes in the perforations of a transparent sphere and leaving between the ends a space for the spark gap, then rig-

idly supporting the opposite ends of the electrodes within the matrix, and then pouring molten insulating material within the matrix and around the electrodes and sphere. 10

In testimony whereof, I have hereunto signed my name.

FREDERICK C. FISK.
